UNITED STATES PATENT OFFICE.

ROBERT A. WILSON, OF WATERTOWN, AND ALLEN P. WILSON, OF WALTHAM, MASSACHUSETTS, ASSIGNORS TO BOSTON PENCIL POINTER COMPANY, OF WALTHAM, MASSACHUSETTS, A CORPORATION OF MASSACHUSETTS.

PENCIL-POINTER.

1,285,528.

Specification of Letters Patent. Patented Nov. 19, 1918.

Application filed December 15, 1913. Serial No. 806,757.

To all whom it may concern:

Be it known that we, ROBERT A. WILSON, of Watertown, in the county of Middlesex and State of Massachusetts, and ALLEN P. WILSON, of Waltham, in the county of Middlesex and State of Massachusetts, have invented certain new and useful Improvements in Pencil-Pointers; and we do hereby declare the following specification, taken 10 in connection with the accompanying drawings, forming a part of the same, to be a full, clear, and exact description thereof.

The invention relates to pencil pointers and has for its object to provide an improved form of receptacle for receiving and holding the chips which are removed from the pencil in the sharpening operation.

One feature of the invention consists in providing a chip-receptacle which is removably mounted upon the pencil pointer in a novel manner, and is automatically locked in engagement therewith.

Another feature consists in providing the chip-receptacle with an adjustable chuck or 25 pencil-holding device.

Another feature consists in inclosing the chip-receptacle and providing such inclosed receptacle with a transparent portion.

To these ends the invention consists in 30 the novel construction and arrangement of parts hereinafter described and more particularly set forth in the claims.

In describing the invention in detail, reference will be had to the accompanying drawings, in which—

Figure 1 is a side elevation of my novel pencil pointer.

Fig. 2 is an end view of the same.

Fig. 3 is a horizontal section on line $\alpha-\alpha$, Fig. 2.

Fig. 4 is an end view of the pencil pointer with the chip-receptacle removed.

Fig. 5 is a side view of Fig. 4 showing the holder for the chip-receptacle in section.

Fig. 6 is a vertical section on line $y-y$, Fig. 1.

Figs. 7, 8 and 9 are detail views of the pencil holding chuck.

Referring to the drawings 1 represents 50 the standard of the machine, which is provided with a suitable foot-portion 2, by means of which it may be secured to a suitable support. The standard 1 has formed integral therewith a head portion 3 and an

elongated bearing 4 for the shaft of the 55 cutter-carrier. The head-portion 3 is recessed and is provided with a series of internal gear-teeth 5, as shown in Fig. 4. The cutter-carrier 6 is provided with a shaft 7 journaled in the elongated bearing 4 and 60 provided at one end with a handle 8 and at the other end with a tubular pencil-guiding portion 9. Mounted in the cutter-carrier 6 are two rotary cutters 10 having spiral cutting blades and provided at one end with 65 gears arranged to mesh with the internal gear-teeth 5 in the head portion.

Mounted upon the head 3 is a chip-receptacle holder 11 which comprises a split body portion clamped upon said head 3 by a 70 screw 12 mounted in lugs 13. Pivoted upon the screw 12 between the lugs 13 is a latch 14, which is constructed and arranged to normally rest in its closed position. Projecting from the holder 11 on opposite sides 75 of the pencil-guide 9 are two rods 15 which serve as supports for the chip-receptacle 16.

Said chip-receptacle 16 consists of two end portions 17 and 18 connected together by rods 19, mounted in lateral projections 20 80 upon opposite sides of each of said end portions. Each lateral projection 20 is provided with a hole 21 extending through the same of such a size as to permit the rods 15 to slide freely therein. Said projections 85 20 are also provided with inwardly extending annular flanges 22, which are adapted to receive the ends of the tubular rods 23, as shown in Fig. 3. The inner surface of each of the end portions 17 and 18 is provided 90 with a groove 24 extending completely around the same and formed by turning over the edge 25, and providing a parallel wall 26, as shown in Fig. 6. Clamped between the end portions 17 and 18, with its 95 edges engaging the groove 24, is a transparent oval casing or shell 27, which is preferably constructed of celluloid.

Mounted in a recess upon the inner surface of the end portion 17 is an adjustable 100 chuck, or pencil-holder, which comprises a series of jaws 28 mounted to move across an opening 29 in alignment with the pencil guide 9, and arranged to be operated by a lever 30 extending through a slot 31 in the turned-over edge 25 of the end portion 17. The lever 30 is adapted to be moved in one direction by the hand of the operator and in the

opposite direction automatically by means of the spring 32, shown in Fig. 6.

With the above construction it will be seen that the chip-receptacle 16 can be readily

5 slid upon the rods 15 and that the latch 14 will be raised by the turned-over edge 25 to permit the same to pass thereunder, and that when said edge has passed thereunder, the latch will fall by gravity and engage

10 said turned-over edge 25 and lock the chip receptacle 16 in engagement with the holder 11, as shown in Fig. 1. It will also be seen that the adjustable chuck will grip pencils of varying sizes and hold them in proper po-

15 sition during the sharpening operation, and that the transparent casing in the chip-receptacle will permit the operator to observe the sharpening operation and the amount of chips that have accumulated in the chip-

20 receptacle.

It will also be seen that the holder 11 can be readily turned about the head 3 so as to permit the standard 1 to be set in an upright or horizontal position as desired.

25 What I claim as my invention and desire to secure by Letters Patent is:

1. In a pencil pointer, the combination with a stand having a head, of a cutter-carrier, cutters journaled in said carrier, a 30 holder adjustably mounted upon the head, a chip receptacle slidably mounted upon said holder, and means for automatically locking said chip-receptacle in engagement with said holder as it is slid on the holder.

35 2. In a pencil pointer the combination with a stand having a head, of a cutter-carrier, cutters journaled in said carrier, a

holder comprising a split body portion, lugs upon each side of the split portion of said body, a screw mounted in said lugs, a latch pivoted upon said screw between said lugs, two bars projecting from said split body portion, and a chip-receptacle slidably mounted upon said projecting bars and locked in engagement with said holder by 45 said latch.

3. In a pencil pointer the combination with a stand having a head, of a cutter-carrier, cutters journaled in said carrier, a holder mounted upon the head, a chip-receptacle mounted on said holder and a pencil holder upon the inside of said chip-receptacle.

4. In a pencil pointer the combination with a stand having a head, of a cutter-carrier, cutters journaled in said carrier, a holder mounted upon the head, a chip receptacle mounted on said holder and an adjustable pencil holder upon the inside of said chip receptacle.

5. In a pencil pointer the combination with a stand having a head, of a cutter-carrier, cutters journaled in said carrier, a holder mounted upon the head, a chip receptacle mounted on said holder, said chip 65 receptacle comprising a transparent casing having non-transparent end portions and an adjustable pencil holder mounted in one of said end portions.

ROBERT A. WILSON.
ALLEN P. WILSON.
